ANTITHEFT DEVICE

Homer T. Flack, White, Pa.

Application December 5, 1933, Serial No. 701,026

1 Claim. (Cl. 88—85)

This invention relates to what may be termed an anti-theft device and consists in the provision of a panel adapted to form a wall, partition or the like of a cage, as for example a cashier's cage in a bank, and suitably equipped to effectively guard against theft on the part of one outside the cage posing, as for example, as a customer.

A further object of the invention is to provide a device of the character above mentioned which will be suitable for use not only in conjunction with banks, but also on railway mail cars, cashier booths and the like.

The invention together with its objects and advantages will be best understood from a study of the following description taken in connection with the accompanying drawings wherein:

Figure 1 is a front elevational view of the device.

Figure 2 is a longitudinal sectional view taken substantially on the line 2—2 of Figure 1.

Figure 3 is a detail sectional view taken substantially on the line 3—3 of Figure 2.

Figure 4 is a fragmentary horizontal section looking downwardly upon a receptacle forming part of the invention.

Figure 5 is a fragmentary vertical sectional view taken on the line 5—5 of Figure 4, and

Figures 6 and 7 are detail sectional views taken substantially on the lines 6—6 and 7—7 respectively of Figure 5.

Referring to the drawings by reference numerals it will be seen that the invention consists in the provision of a panel 11 suitable to constitute a wall, partition or the like of a cashier's booth or similar structure. On each side 12, 13 thereof, the panel is provided with a ledge or shelf 14 mounted at a suitable elevation. Suitably mounted above each shelf 14 and adjacent thereto is an inclined mirror 15. At its upper end the panel is provided with a transverse opening 16 and disposed in operative position to the opening 16, on the sides 12, 13 of the panel are oppositely inclined mirrors 17 hinged to the panel 11 as at 18. Suitable means for securing the mirrors 17 at the desired angular adjustment are provided and indicated generally by the reference numeral 19. From the foregoing it will be seen that a person standing at one side of the panel, for example, the side 12, can by looking in the mirror 15 see the person at the opposite side of the panel, the last named person being thus seen due to the reflection caused by the arrangement of mirrors 15 and 17 at opposite sides of the panel.

Slightly above the upper ends of the mirrors

15 the panel 11 is provided with an opening 20 and swingable through the opening 20 from one side to the other of the panel 11 is a tray 21. The tray 21 is substantially V-shaped in cross section and is pivotally mounted as at 22. At the 5 opening 20 suitable shields 23 are provided on the sides 12, 13 of the panel and are of such a construction, and so arranged relative to the tray 21 as to cooperate therewith for preventing any 10 would be "hold-up" man from placing a firearm in position for firing through the aperture 20.

To permit persons on opposite sides of the panel 11 to converse with one another without danger to the cashier there is also provided above the opening 20 a narrow horizontal slot 24, and 15 what may be termed speaking tubes 25, of the cross sectional shape clearly shown in Figure 2 are mounted on the sides 12, 13 of the panel and have integral upwardly extending flanges or attaching portions 25a disposed opposite the slot 20 20 in a manner effective to prevent shooting through the tubes 25, and thus further safeguarding the cashier.

To accommodate larger and more bunglesome articles than can be accommodated by the tray 21 there is provided on the side 13 of the panel a receptacle 26 that is open at each end, and at the end thereof secured to the panel 11 registering with a suitable opening 27 provided in the panel. Vertically slideable closures 28, 29 are provided for the ends of the casing or receptacle 26 25 and these slides 28, 29 operate in suitable guide 30 grooves 30 provided on the walls of the casing 26.

Secured in sliding position on the top of the receptacle or container 26 through the medium 35 of straps 31 is a suitable knob equipped bolt 32 that has the ends thereof adapted to engage in openings 33, 34 provided in the upper ends of the closures 28, 29 in a manner clearly shown in Figure 5. For limiting sliding movement of the 40 bolt 32 the same, adjacent each end thereof, is provided with a suitable laterally extending pin 35. As shown in Figure 5 when one end of the bolt 32 is projected through the opening 34 in the closure 29 the latter is thereby locked in 45 position against being raised vertically while the closure 28 which is readily accessible to the person on the side 13 of the panel can be easily raised by him so as to permit a person at the side 12 of the panel to place within the casing 26 50 such article as desired. It will be further noted that by this arrangement when one of the closures, for example the closure 28 is in raised position the retraction of the bolt 32 cannot be made 55 so that the closure 29 must remain in locked and

closed condition as long as the closure 28 is in raised position, and vice versa.

It will thus be seen that in accordance with this invention a person, such as for example a cashier or the like at the side 13 of the panel, may readily see and communicate with the person at the side 12 of the panel and that money, passbooks, and the like may be readily passed between the persons without any danger whatever 10 to the cashier.

Upon occasion, as for example where the panel 11 is not of sufficient height as to have the opening 16 out of reach of a man of normal stature, a shield, such as for example a shield 36 may be 15 employed, and the same, as shown in Figure 2 is mounted on the upper end of the panel 11 on the side 12 thereof which is of course "the customer's side" and this shield completely receives therein the mirror 17 on the side 12 of the panel 20 and will effectively guard against anyone being able to place a pistol in proper position relative to the opening 16 for the purpose of firing upon the cashier or other person at the side 13 of the panel.

While I have herein shown and described the preferred embodiment of the invention it is to be understood that I do not wish to limit myself to the precise details of construction, combination and arrangement of elements as herein 5 illustrated and described, other than may be necessary to meet the requirements of the prior art.

Having thus described my invention, what I claim as new is:

In a device of the character described, a panel provided on each side thereof adjacent the lower end with a counter and a mirror supported by the panel, and inclined downwardly toward the counter, said panel adjacent its upper end being 15 provided with an opening, mirrors hinged to the panel at opposite sides thereof adjacent the upper edge of the opening and being inclined downwardly, and brace means connected with the second named mirrors for supporting the same at 20 the desired angle of adjustment.

HOMER T. FLACK.
